[57] CLAIM

The ornamental design for a combined chair and storage unit, as shown and described.

DESCRIPTION

FIG. 1 is a left-front perspective view of a combined chair and storage unit showing my new design;

FIG. 2 is a front elevational view;

FIG. 3 is a rear elevational view;

FIG. 4 is a top plan view;

FIG. 5 is a bottom plan view;

FIG. 6 is a right side elevational view, the left side being a mirror image thereof; and,

FIG. 7 is a left-front perspective view showing the storage compartments in opened condition.

FIG. 1

FIG. 2

FIG. 3

FIG. 4

FIG. 5

FIG. 6

FIG. 7
